US0D1016436S

(12) United States Design Patent (10) Patent No.: US D1,016,436 S
(45) Date of Patent: * Mar. 5, 2024

(54) BUTTON PIN FOR JEANS

(71) Applicant: MAVI GIYIM SANAYI VE
TICARET ANONIM SIRKETI,
Istanbul (TR)

(72) Inventor: Ebru Tugalan, Istanbul (TR)

(73) Assignee: MAVI GIYIM SANAYI VE
TICARET ANONIM SIRKETI,
Istanbul (TR)

() Term: 15 Years

(21) Appl. No.: 35/514,533

(22) Filed: Feb. 18, 2022

(80) Hague Agreement Data

Int. Filing Date: Feb. 18, 2022

Int. Reg. No.: DM/221384

Int. Reg. Date: Feb. 18, 2022

Int. Reg. Pub. Date: Jul. 1, 2022

(51) LOC (14) Cl. 02-02

(52) U.S. Cl.

USPC D2/853

(58) Field of Classification Search

USPC D2/640, 641, 643, 853, 837; 112/475.15;
24/103

CPC A41F 1/02
